CLAIM

The ornamental design for a cabinet basket as shown and described.

DESCRIPTION

FIG. 1 is a perspective view of a cabinet basket showing the new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detailed view of the portion 9 in FIG. 1;

FIG. 10 is an enlarged detailed view of the portion 10 in FIG. 2;

FIG. 11 is an enlarged detailed view of the portion 11 in FIG. 2;

FIG. 12 is an enlarged detailed view of the portion 12 in FIG. 3; and,

FIG. 13 is an enlarged detailed view of the portion 13 in FIG. 8.

The evenly dashed broken lines show portions of the cabinet basket that form no part of the claimed design. The dot-dash broken lines illustrate the borders of the enlarged detailed views and form no part of the claimed design.

1 Claim, 13 Drawing Sheets
